(57) **CLAIM**

The ornamental design for a belt, as shown and described.

DESCRIPTION

1.1 is a front perspective view of a belt of the claimed design;

1.2 is a front elevational view of the belt shown in FIG. **1.1**;

1.3 is a rear elevational view of the belt shown in FIG. **1.1**;

1.4 is a right elevational view of the belt shown in FIG. **1.1**;

1.5 is a left elevational view of the belt shown in FIG. **1.1**;

1.6 is a top plan view of the belt shown in FIG. **1.1**;

1.7 is a bottom plan view of the belt shown in FIG. **1.1**; and

1.8 is a perspective of the belt shown in FIG. **1.1** in an alternate configuration.

The claimed design is shown in solid lines in the figures. The broken lines represent stitching and form no part of the claimed design.
